Lester Cohen, Spring Valley, and Willard H.
Reineking, San Diego, Calif.

Application January 12, 1953, Serial No. 23,104

Term of patent 14 years

(Cl. D34—15)

To all whom it may concern:

Be it known that we, Lester Cohen, a citizen of the United States and a resident of Spring Valley, county of San Diego, California; and Willard H. Reineking, a citizen of the United States and a resident of San Diego, county of San Diego, California, have invented a new, original, and ornamental Design for a Monorail Toy, of which the following is a specification, reference being had to the accompanying drawings forming part thereof.

Figure 1 is a perspective view of a monorail toy embodying our new design.

Figure 2 is a front view thereof.

Figure 3 is a rear view thereof.

Figure 4 is a side view taken as from a left-hand side of Figure 3.

Figure 5 is a side view of the opposite side from Figure 4.

Figure 6 is a top view.

Figure 7 is a bottom view.

The broken line showing of a monorail and support is for illustrative purposes only.

We claim:

The ornamental design for a monorail toy, as shown and described.

LESTER COHEN.

WILLARD H. REINEKING.
